UNITED STATES PATENT OFFICE.

LOUIS H. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

MACHINE FOR SHAPING MATRICES.

1,392,621.

Specification of Letters Patent.

Patented Oct. 4, 1921.

Application filed August 5, 1919. Serial No. 315,485.

To all whom it may concern:

Be it known that I, LOUIS H. BECHMAN, a citizen of the United States, residing at Battle Creek, in the county of Calhoun and State of Michigan, have invented certain new and useful Improvements in Machines for Shaping Matrices; and I hereby declare that the following is a full, clear, and exact description thereof, reference being had to 10 the accompanying drawings, which form part of this specification.

This invention is a novel improvement in means for shaping the matrices used in casting stereotype-plates and the like before the 15 matrices are inserted in the casting boxes. Primary objects of the invention are to preliminarily shape the matrix; and to partially dry and set the matrix.

Further objects are to so construct the 20 form around which the matrix is shaped that any steam developed by the heating of the matrix will readily escape; and to so construct the flexible bending sheet as to provide for the ready escape of steam or 25 moisture and at the same time enhance the flexibility of the sheet; also to provide means for supporting the flexible sheet when partially opened in such position that while permitting the ready insertion or removal 30 of the matrix, it will facilitate the positioning of the matrix around the form preparatory to bending it; and will always be retained in a position for convenient manipulation by the operator.

35 The invention consists in a novel apparatus by which the matrix can be readily simultaneously shaped and heated to dry same if desired, such apparatus being inexpensive in construction, durable, exceedingly simple in operation, and producing very valuable practical results.

I will explain the invention in connection with the accompanying drawings which illustrate practical embodiments thereof; 45 and to enable others to readily adapt and use the same. In the claims I have summarized the essentials of the invention and the novel construction and combination of parts, for all of which protection is desired.

50 In said drawings:

Figure 1 is a side elevation of a complete apparatus for shaping tubular stereotype plates.

Fig. 2 is an enlarged elevation of the upper part of such apparatus, viewed at 55 right angles to Fig. 1.

Fig. 3 is a top plan view of Fig. 2 showing the shaping sheet open and a matrix inserted in position preparatory to being shaped.

Fig. 4 is an enlarged detail transverse section of part of the form.

Fig. 5 is a front view of an apparatus for shaping semi-cylindric stereotype plates.

Fig. 6 is a transverse sectional view on 65 line 6—6, Fig. 5.

The apparatus shown in Figs. 1 to 4 is especially constructed for shaping matrices used in casting tubular stereotype plates; and as shown comprises a cylindric form 1 70 which may be of cast metal and should be of an external diameter approximately corresponding to the length or width and curvature of the finished tubular stereotype plate; or of a diameter, plus the thickness of the 75 matrix, approximately corresponding to the internal diameter or curvature of the box in which the matrix is to be used in casting the plate. And this form should be slightly wider or longer than the length or width of 80 the matrix to be treated thereon.

The form 1 is preferably hollow and may be supported on end in any suitable manner, and is preferably arranged in a vertical position. As shown it is mounted upon a 85 stand or base 2; which may be of any suitable construction; and if desired the stand and form may be cast integral.

Each form has in its exterior surface a series of small parallel grooves or channels, 90 indicated at 1^a, preferably extending longitudinally thereof, and the steam or vapor evaporated from the matrix in the drying can readily escape through such channels. These channels or ducts are preferably so 95 close together and so narrow in width that they will not interfere with or prevent the proper curving of the matrix while at the same time they provide for the rapid escape of the hydrous vapors. It has been demonstrated in practice that such channels greatly facilitate the evaporation and drying of the matrix on the form.

The form may be heated by any suitable means. In the drawings a gas burner 5 is 105 indicated, located within the lower end of

the form, and gas can be supplied to said burner by a pipe 5^a that may extend through the stand 2 and be connected to any suitable gas supply.

5 Coöperating with this form 1 is a flexible bending sheet 3, which is of sufficient length to entirely surround the form, and approximately corresponds in width to the length of the form.

10 The sheet 3 is preferably made of resilient sheet steel and naturally tends to assume a straight or flat condition, when released. It should be strong but sufficiently pliable to enable it to conform closely to the curved 15 surface of the form and wrap around the same, as in Figs. 1 and 6. To facilitate bending of the sheet, to lighten it, and to provide for escape of moisture evaporated from the matrix in the drying thereof, when 20 clamped by the sheet against the form, the sheet is preferably provided with numerous small perforations, indicated at 3^a, which may be of any suitable diameter and spaced as desired.

25 One edge of this sheet is attached to the form in any suitable manner and the other end is free. In the example shown the attached end of the sheet is secured between two bars or strips 4^a, 4^b, which are attached 30 to the side of the form by bolts 4^c or other suitable means. The bar 4^a corresponds in thickness to a matrix, and therefore separates the end of the sheet from the periphery of the form a distance equal to the thickness 35 of the matrix. The bar 4^a also forms a matrix stop, as it is fastened in position to arrest the edge of a matrix M when inserted between the sheet and the form, as indicated in Fig. 3.

40 The free end of the sheet 3 may be provided with a handle 4^d of any suitable construction by which it can be conveniently operated, and this handle may be engaged by any suitable retaining device to hold the 45 sheet in closed position. A catch 4^e pivoted on the bar 4^b is indicated in the drawings.

As the sheet 3 is flexible and springy it would, unless restrained, fly too far open when disengaged from the retaining device 50 or catch; and to prevent this and to hold the sheet in such position that it will act to guide the matrix into position around the form, and so that it can be conveniently closed upon the matrix thereafter, I pref- 55 erably provide a sheet supporting and retaining device of any suitable construction.

In the example illustrated in the drawings a vertically disposed rod 6 is shown attached to the top and bottom of the form by end 60 members 6^a and 6^c. This rod is located about 90 degrees removed from the bar 4^b in Figs. 1-3; and about 45 degrees removed from the bar 4^a in the form shown in Figs. 5 and 6. The part 6^a supports the lower 65 edge of the sheet which slides thereon in

opening and closing; and to facilitate the sliding movement of the edge of the sheet 3 on the part 6^a, I preferably provide it with a shield 6^b, on which the sheet can readily slide.

70 When the sheet 3 is disengaged from the catch 4^e it will by reason of its natural resiliency spring open to the position shown in Figs. 2 and 3, being supported by the shield 6^b and arrested by contact of its handle 4^d with the vertical part of the rod 6.

I do not consider the invention restricted to the particular construction shown for supporting and holding the sheet 3 in position when opened.

80 The apparatus shown in Figs. 5 and 6 is more particularly adapted for shaping matrices for semi-cylindrical stereotype plates; and the form 1^x is correspondingly shaped. The other parts are constructed substantially like the corresponding parts in Figs. 1 to 4 and are correspondingly lettered. In this case, however, the hook 4^e is attached to a stop bar 4^f approximately 85 diametrically opposite bar 4^a.

90 When it is desired to prepare a matrix, the flexible sheet 3 is opened, as indicated in Fig. 3; then the matrix is inserted between the sheet and form and its end alined against the bar 4^a, the matrix is readily introduced edgewise between the sheet 3 and the form and is guided into position by the curvature of the sheet. Then the sheet 3 is wrapped, or closed, around the form and matrix, as indicated in Figs. 1 and 6, bringing the matrix easily around and closely against the form and holding the matrix between the form and the sheet. In this way the matrix is readily shaped to fit the curvature of the form. By fastening the sheet by catch 4^e the matrix can be held 100 against the form for any length of time desired. A matrix may be shaped on the apparatus shown in Figs. 5 and 6 in like manner.

105 The matrix may be wholly or partially dried and set while it is so held around the form, by heating the form; and such heated form will cause the matrix to rapidly dry and harden as the moisture in the matrix evaporates and escapes rapidly through the channels 1^a in the form and perforations 3^a in the sheet.

110 When it is desired to remove the matrix the sheet is opened up and the matrix can be readily drawn off the form, as is obvious.

115 An important practical advantage of my invention is the facility with which the matrices can be "backed" when and where it is desirable to do so prior to shaping. When matrices are made from type-matter having considerable blank spaces it is necessary to paste backing on the reverse side of the mats to support these blank portions against the pressure of the metal 120

when casting. A great difficulty always heretofore experienced with this backing has been that it had to be pasted on the matrix while flat and then dried on the 5 matrix on a steam table with the matrix flat. As a result when the matrix was afterward curved into a casting box pieces of the backing would break loose partially or entirely, and either fall off or get out of 10 position thus causing trouble and defective plates, as the curving of a flat matrix that had been baked hard would separate the backing which was simply pasted thereto. This trouble has always been experienced 15 with matrices for semi-cylindrical stereotype plates and also for tubular plates as heretofore prepared.

My invention obviates these objectionable features and annoyances because the matrix 20 with the backing strips can be placed in the shaper while same are still damp and are dried while shaped, and therefore become set in the shape in which they are wanted for use; and when such shaped and backed 25 matrix is placed in the casting boxes it is in perfect condition. This result has never before been accomplished with the heretofore known "matrix roasters" or "scorchers" as they have never provided for the escape 30 of steam and vapors which provision enables very moist matrices to be treated in my shaper.

By thus perfecting the condition of the matrix and backing at one operation I obtain 35 the proper depth for the plate where blank or white space is required, and obviate a great deal of the routing and chiseling out of such portions which has hitherto been necessary on plates after they were cast 40 from a flat dried matrix because of the impossibility of properly backing up the matrix prior to drying with the means and methods of drying it heretofore in use, and because the backing will break away from 45 a flat dried matrix when the latter is curved by inserting it in a casting box.

Another great practical advantage of my matrix shaping and drying apparatus is its 50 simplicity, which enables the matrix to be placed therein, and shaped and dried very rapidly; the drying being greatly facilitated by the channels in the form and the perforations in the sheet through which the evaporated steam or moisture readily escapes, 55 and which channels and perforations insure the desired uniform bone-dry hardness of the curved surfaces of the matrix. With my apparatus a matrix can be rapidly and thoroughly dried out in a very few moments 60 and be ready for immediate use when removed therefrom; and my apparatus not only performs the function of shaping the matrix but can also perform the functions of a matrix drying machine and matrix 65 "scorcher."

Claims—

1. Apparatus for shaping stereotype matrices comprising a curved form having a multiple of small channels in the surface against which the matrix is placed for the escape of steam or vapor exuded from the matrix, and means for bending a matrix around said form. 70

2. Apparatus for shaping and drying matrices for casting stereotype plates, comprising a curved form having a multiple of small channels in the surface against which the matrix is placed for the escape of steam or vapor exuded from the matrix, means for bending a matrix around said form, and 80 means for heating the form. 75

3. Apparatus for shaping matrices for casting stereotype plates, comprising a curved form having a multiple of small channels in the surface against which the matrix is placed for the escape of steam or vapor exuded from the matrix, a flexible sheet adapted to flex a matrix around said form, and means for holding the sheet in wrapped position to retain the bent matrix 90 in place. 85

4. In apparatus for shaping and drying stereotype matrices, the combination of a tubular cylindric form having a multiple of parallel channels in the surface against which the matrix is placed; a flexible metallic sheet adapted to curve a matrix around the form, means for fastening the sheet to the form, and means for heating the form when a matrix is wrapped between the sheet 100 and the channeled surface of the form. 95

5. Apparatus for shaping stereotype matrices comprising a stationary cylindric form having a multiple of small channels in the surface against which the matrix is placed, and a flexible metallic sheet having one end connected with the form and adapted to be wrapped around such form to curve a matrix inserted between it and the channeled surface of said form. 105 110

6. Apparatus for shaping and drying matrices for casting stereotype plates; comprising a stationary curved form having exterior parallel channels, a flexible sheet having one end connected with the form and adapted to be wrapped around it to bend a matrix inserted between the sheet and form, means for heating the form, and means for holding the sheet in wrapped position to retain the bent matrix in place. 115

7. In apparatus for shaping stereotype matrices, the combination of a tubular cylindric form, a flexible metallic sheet adapted to be wrapped around the form, means for fastening the sheet to the form, said means forming a matrix stop adjacent the attached portion of the sheet, and means for detachably fastening the free end of the sheet to the matrix stop when a matrix is wrapped between the sheet and form. 125 130

8. Apparatus for shaping and drying matrices for casting stereotype plates, comprising a curved form having channels in the surface against which the matrix is placed for the escape of steam or vapor exuded from the matrix, and a flexible perforated sheet for bending a matrix around said form.
9. Apparatus for shaping matrices for casting stereotype plates, comprising a curved form having channels in the surface against which the matrix is placed for the escape of steam or vapor exuded from the matrix, a flexible perforated sheet adapted to flex a matrix around said form, and means for holding the sheet in wrapped position to retain the bent matrix in place.
10. In combination a hollow cylindric form, a stand supporting this form on end, a flexible sheet attached to and adapted to be bent around the form to bend a matrix around it, and means for heating the form.
11. In combination a tubular cylindric form externally channeled, a stand supporting said form in a vertical position, a bar attached to the form and extending longitudinally thereof, a flexible sheet attached to the said bar and adapted to be closed around the form to bend and hold a matrix thereagainst, and means for fastening the free end of the sheet when around the form.
12. In combination a cylindric tubular form, provided with parallel longitudinal channels on its exterior, a flexible metallic sheet attached to the outer side of the form and adapted to be bent around the form to shape the matrix thereagainst, means for fastening the free end of the sheet when around the form, a stand supporting the form, and means for internally heating the form.
13. In combination a tubular cylindric form exteriorly channeled, a stand supporting this form vertically on end, a flexible sheet attached to and adapted to be curved around the form to bend the matrix thereagainst and means for heating the form.
14. In combination a tubular cylindric form externally channeled, a stand supporting said form in a vertical position, a bar attached to the form and extending longitudinally thereof, a flexible sheet attached to the said bar and adapted to be curved around the form to bring the matrix thereagainst, means for fastening the free end of the sheet when around the form, and means for heating the form internally.
15. In combination a curved tubular form, provided with parallel longitudinal channels on its exterior, a flexible perforated metallic sheet attached to the outer side of
- the form and adapted to be bent around the form to shape the matrix thereagainst, means for fastening the free end of the perforated sheet when wrapped around the form, means supporting the form; and means for internally heating the form.
16. In combination a cylindric tubular form provided with parallel longitudinal channels in its exterior; a bar attached to the outer side of the form and extending longitudinally thereof, a flexible metallic sheet attached to the said bar and adapted to be bent around the form to shape the matrix thereagainst, means for fastening the free end of the blanket when around the form, a stand supporting the form in vertical position, and means for internally heating the form.
17. Apparatus for shaping stereotype matrices comprising a curved form against which the matrix is placed, and a flexible resilient metallic sheet connected with the form and adapted to be bent around such form to curve a matrix inserted between it and the channeled surface of said form and means to arrest the sheet when released.
18. Apparatus for shaping and drying matrices for casting stereotype plates, comprising a stationary curved form, a flexible resilient metallic sheet having one end connected with the form and adapted to be wrapped around it to curve around the form, and sheet supporting and arresting devices connected with the form.
19. Apparatus for shaping and drying matrices for casting stereotype plates; comprising a stationary form, a flexible resilient metal sheet having one end connected with the form and adapted to be wrapped around it to bend a matrix inserted between the sheet and form, means for holding the sheet in wrapped position to retain the bent matrix in place, and means for supporting the sheet and limiting its separation from the form when released.
20. In apparatus for shaping stereotype matrices, the combination of a tubular cylindric form, a flexible resilient metallic sheet adapted to be wrapped around the form, means for fastening the sheet to the form, said means forming a matrix stop adjacent the attached portion of the sheet, means for detachably fastening the free end of the sheet to the matrix stop when a matrix is wrapped between the sheet and form, and means for supporting the sheet and limiting its separation from the form when released.

In testimony that I claim the foregoing as my own, I affix my signature.

LOUIS H. BECHMAN.
